UNITED STATES PATENT OFFICE.

HERMANN REICHE, OF MILLSTONE, NEW JERSEY.

IGNITER FOR INTERNAL-COMBUSTION ENGINES.

1,068,930.

Specification of Letters Patent.

Patented July 29, 1913.

Application filed January 23, 1908. Serial No. 412,320.

To all whom it may concern:

Be it known that I, HERMANN REICHE, a citizen of the United States, and a resident of Millstone, in the county of Somerset and

5 State of New Jersey, have invented a new and Improved Igniter for Internal-Combustion Engines, of which the following is a full, clear, and exact description.

This invention relates to certain improvements in that type of igniter for internal combustion engines in which a small quantity of the explosive mixture is compressed in an auxiliary cylinder to such a pressure that it automatically ignites and serves for 15 the ignition of the main charge in the working cylinder.

One object of the invention is to so construct the mechanism for compressing the igniting portion of the gas that this mechanism may be readily applied to any common form of internal combustion engine already manufactured and used, in place of the usual spark plug. The igniting mechanism may be manufactured and sold independently of 25 the engine the same as ordinary spark plugs are manufactured and sold, and may then be applied to the engine by the purchaser.

A further object of my invention is to provide means for controlling the pressure in the igniter, so as to control the time at 30 which the ignition will take place, and thus control the speed of the engine. The controlling mechanism involves means for automatically controlling the timer, so as to automatically govern the engine, and in addition to this, means for manually controlling 35 the same.

Various means may be provided for operating the piston to produce the desired compression of the ignition charge, said means being positively operated from a moving part of the engine, or operated by a spring. In case a spring is used, it may be compressed either by the action of a moving part 45 of the engine, or by the pressure existing within the cylinder immediately after the explosion, or at the end of the compression stroke. In case the spring is used, as above indicated, the spring may be released and 50 the timing of the explosion controlled by the removal of a stop or catch, the movement of which is dependent upon the pressure in the engine cylinder or upon the action of a moving part, or upon fluid pressure in a part of 55 the igniter.

Reference is to be had to the accompany-

ing drawings, forming a part of this specification, in which similar characters of reference indicate corresponding parts in all the figures, and in which—

Figure 1 is a side elevation of a portion of an engine provided with one form of my improved ignition device, in which the compression is brought about by a spring released by the action of a moving part of the engine; Fig. 2 is a longitudinal section through the igniter proper, said section being taken on the line 2—2 of Fig. 1; Fig. 3 is a longitudinal section through another form of my ignition device, in which compression is brought about by the action of a moving part of the engine, and illustrating a second form of governor; Fig. 4 is a longitudinal section through a third form of my improved ignition device; Fig. 5 is an end view thereof; Fig. 6 is a transverse section on the line 6—6 of Fig. 4; Fig. 7 is a transverse section on the line 7—7 of Fig. 4; Fig. 8 is a side elevation of a portion of the tripping or piston-releasing device; Fig. 9 is a transverse section on the line 9—9 of Fig. 4; Fig. 10 is a side elevation of the portion of the operating rod for said releasing device; Fig. 11 is a longitudinal section through a further modification of my improved igniter; Fig. 12 is a longitudinal section of a portion thereof, showing the parts in position at the instant of firing; and Fig. 13 is a transverse section on the line 13—13 of Fig. 11.

In all of the forms of my improved ignition device, the igniter proper is preferably so constructed that it may be threaded into the opening in the cylinder wall or cylinder head, into which the ordinary spark plug is normally inserted, and the attachments for operating the igniter proper are such that they may be readily applied to an engine without necessitating the special designing of the engine to adapt it for the igniter.

In the specific form illustrated in Figs. 1 and 2, the igniter proper includes a body 10, having a threaded portion 10^a adapted for insertion into the threaded opening in the engine A. The inner end of the body is constructed to form an auxiliary or ignition cylinder 11, having a piston 12 operating therein and having a very small discharge opening 13 at the inner end, through which the gases may escape into the engine cylinder, particularly at the instant of explosion. At the outer end of the body 10, there is pro-

vided a casing made up of two telescoping sections 14 and 15. The section 14 is rigidly secured to the body, and is provided with a nipple 16, or other suitable means, whereby the casing may be placed in communication with a source of explosive mixture supply. The outer section 15 of the casing is threaded into the outer end of the section 14, and at its outer end carries a threaded cap 17. The plunger or piston 12 extends through the casing and through the cap 17, the latter serving as a guide or lateral support for the piston. Within the casing section 15, there is provided a heavy coil spring 18, one end of which engages with the cap 17, and the other end of which engages with a circumferential flange 19 on the hollow piston 12. The strength of this spring is such that when the plunger or hollow piston 20 is released, it will compress the gas in the cylinder 11 to such a pressure that it will instantly ignite and the flame will issue through the orifice 13 to ignite the main charge in the working cylinder. For admitting the explosive mixture to the cylinder 11, the nipple 16 is connected to the carbureter or to the explosive mixture supply conduit, and the portion of the hollow piston 12 which is within the casing section 14 is 30 provided with one or more inlet ports 20. The piston is formed of a tube of the desired diameter and having its lower end closed by a valve 21, the valve stem of which extends to adjacent the upper end of the piston. This terminal valve is normally held closed by a light spring 22, engaging with suitable stops carried by the valve rod and piston, but at the time of the suction stroke of the piston, the partial vacuum created 40 will open the valve 21 and the explosive mixture will flow through the nipple 16, the casing section 14, and the ports 20, to the interior of the piston, and thence past the valve 21 to the cylinder 11. For preventing the escape of the charge past the piston, a suitable packing 23 is provided within the body and surrounding the piston and held in place by a spring 24, the tension of which is controlled by a nut or gland 25 threaded 50 into the outer end of the body and within the casing section 14. Operatively connected to the piston at its outer end is means for normally holding the piston in its outermost position with the spring compressed, 55 and so constructed as to release the piston at the desired time to cause a compression of the ignition charge. Preferably, the piston carries a laterally-extending arm 26, held between collars on the piston and having its 60 outer end in engagement with a cam 27. The cam is of such shape that once during each revolution, the arm is released and the piston permitted to descend into the cylinder under the influence of the spring 18. 65 The compression of the charge ignites the

same, and the pressure in both the main cylinder and the auxiliary cylinder immediately rises to the maximum. This normally tends to force the piston 12 back against the action of the spring 18 and to compress the latter. The cam 27 is therefore preferably so formed that it will engage with the arm 26 before the pressure in the cylinder is decreased due to the movement of the main piston. Thus, the work of raising the piston 12 against the action of the spring is done by the pressure of the gas in the cylinder rather than by the cam, the latter serving merely to hold the spring compressed until the proper time arrives for igniting the next charge. For controlling the tension of the spring, the movement of the piston and the pressure to which the initial charge is compressed, the casing section 15 is threaded to the casing section 14 and the piston is so connected to the casing section 15, that the relationship of the two sections may be adjusted, without affecting the adjustment of the section 15 and the piston. The interior of the section 15 is preferably provided with longitudinal grooves 15^x, which engage with the periphery of the flange 19, so that a rotation of the casing section causes a simultaneous rotation of the piston, and the cap 17 is threaded to the section 15, so that the tension of the spring may be varied without rotating either the casing section or the piston. The outer end of the piston is rotatably mounted in the end of the arm 26, so as to permit of the necessary rotation of the piston in adjusting the device. For rotating the cam and for controlling the same so as to vary the time of ignition, I provide a shaft 28 mounted in suitable bearings secured to the cylinder or engine frame and held from longitudinal movement by means of two collars 29, 29, in engagement with opposite sides of one of the bearings. The cam 27 is mounted on a sleeve 30, and said sleeve is mounted directly on the shaft. The sleeve is keyed to the shaft, so that it may move longitudinally thereof but cannot rotate in respect thereto, and the cam is keyed to the sleeve so as to prevent rotation of the cam in respect to the sleeve, save when the sleeve is moved longitudinally. The keyway in the outer surface of the sleeve is in the form of a helix, and the cam is held from longitudinal movement by suitable bearings upon opposite sides thereof. When the sleeve is moved longitudinally in respect to the shaft, the cam is caused to slightly vary its angular adjustment in respect to the shaft, due to the helical formation of the keyway in the sleeve. Any suitable means may be provided for moving the sleeve longitudinally to control the position of the cam, and thus the time of ignition. As shown, I employ a lever 31, having one end thereof pivoted to the cylinder 130

der head of the engine and having engagement with a collar 32, rotatably mounted on the sleeve but held from longitudinal movement in respect thereto. For rotating the shaft and the cam, I provide a wheel 33 rotated from a moving part of the engine and so connected that its relationship thereto remains constant. For a two-cycle engine, the wheel 33 is so connected that it rotates at the same time as the shaft crank, while for a four-cycle engine, it is so connected as to rotate at one-half the speed of the crank shaft. The wheel may be operated by a series of gears, by a chain or by other suitable connecting means. The wheel is mounted on a sleeve 34, somewhat similar to the sleeve 30, and this sleeve 34 is also mounted on the shaft. The sleeve is keyed to the shaft, so as to permit of a longitudinal movement but to prevent a rotation in respect to the shaft. The wheel is keyed to the sleeve, but the keyway in the sleeve is of helical form so that a longitudinal movement of the sleeve rotates the shaft to a slight extent and varies the angular adjustment of the wheel in respect to the shaft. Suitable means are provided for moving the shaft longitudinally in accordance with the speed of the engine, so as to automatically govern the engine. This means preferably comprises a collar 35, secured to the shaft, a plurality of links pivotally connected to the collar and to the end of the sleeve, and weights or balls 36 normally tending to fly outward due to centrifugal force, and to draw the sleeve toward the collar, the action of centrifugal force being normally resisted by a suitable spring 37. It is well-known that the speed of the engine may be controlled by advancing or retarding the time of ignition, and it will be noted that the mechanism for transmitting the motion to a cam permits of not only an automatic control but also a manual control. A variation in the speed of the engine causes a movement of the centrifugal governor to draw the sleeve 34 longitudinally, and to vary the angular adjustment of the wheel 33 and the shaft, while a movement of the lever 31 causes a longitudinal movement of the sleeve 30 and a variation in the angular adjustment of the shaft and the cam. Either the manually-controlled governing mechanism or the automatic governor may be used independently of the other, and the speed of the engine may thus be held substantially constant at any desired speed.

In the specific form of igniter illustrated in Fig. 3, instead of relying solely upon the action of a coil spring for producing the compression within the igniting chamber, I employ an auxiliary piston 40 for aiding in the compression of the gas, and also provide means operated from a moving part of the engine for positively moving the hollow piston 12 at the desired time; I also provide a

somewhat different form of governor. The body 10^b is substantially identical with the body 10 of the form shown in Fig. 2, save that the lower end thereof is open for the reception of the hollow piston 40, carried by the main piston B of the engine. The engine piston B is preferably provided with an aperture leading to the rear side thereof, so that air or other cooling fluid may circulate within the hollow piston 40 to facilitate the cooling thereof. The cylinder 11^a is provided with a plurality of discharge vents or passages 13^a, normally closed by the hollow piston 12 and serving to permit an escape of the flame from the ignition cylinder to the main cylinder at the instant of the preliminary explosion. At the outer end of the body 10^b, is the casing formed of two sections 14 and 15, having the details of construction substantially the same as the casing shown in Fig. 2. In this form I have illustrated means for lubricating the hollow piston 12, said means including an oil opening 41, normally closed by a screw, and a diaphragm 42, serving to prevent the passage of lubricating oil to the inlet ports 20 of the piston. For reciprocating the piston 12, I provide a longitudinally-movable bar made up of two sections 43 and 44 adjacent the engine cylinder and mounted within any suitable form of guide. One end of the bar section 44 carries a laterally-extending arm 45, engaging with the outer end of the piston 12, and the opposite end of the bar section 43 carries a laterally-extending arm 46, having a roller 47 journaled in the outer end thereof and in engagement with a cam 48 rotated from a moving part of the engine. The action of the cam serves to intermittently move the bar longitudinally and the connecting arm 45 causes the piston 12 to be depressed. The cam is preferably conical and so constructed that it may be moved to vary the movement of the rod or may be locked to prevent movement thereof. The two bar sections are held extended to their maximum length by a coil spring 49, and the roller 47 is held in engagement with the cam by a coil spring 50, engaging with the bar section 43 and with the support or guide for the bar. In the operation of this form of igniter, the piston 40 enters the cylinder 11^a just before the engine piston reaches the end of the compression stroke. The upward movement of the piston causes a compression of the gas within this cylinder, and at about this time the cam 48 operates to move the piston 12 toward the piston 40 and still further compresses the ignition charge in the cylinder 11^a. When the pressure within this cylinder reaches the predetermined limit, the gas spontaneously ignites and the great increase in pressure causes the piston 12 to move outward against the action of the spring 49 and the spring 18^a, until the

ports or vents 13^a are uncovered and the gas can rush outward into the main charge to ignite the same. The main compressing action is caused by the piston 12, while the piston 40 serves largely as a means for closing the end of the cylinder. If desired, the piston 40 may be relied upon solely as the compression piston, in which case I lock the cam 48 against movement, whereby the outer end 10 of the piston 12 is also locked against longitudinal movement, save by the compression of the spring 49. Acting in opposition to the spring 18^a, which aids the spring 49 in resisting the outward movement of the piston 12, I preferably provide a second spring 52, acting between the flange 19 and the inner end of the casing 15. This spring serves to retain the outer end of the piston 12 in engagement with the arm 45. For 20 varying the time of ignition and thus varying the speed of the engine, I provide an automatic governor varying somewhat in detail from that shown in Fig. 1. The longitudinally-movable shaft 28^a is mounted in 25 suitable bearings and is provided with a wheel 33^a keyed thereto but held from longitudinal movement. The motion is transmitted from the crank shaft of the engine to the wheel 33^a in any suitable manner. 30 The shaft at one end thereof is connected by a suitable collar 53 to a longitudinally-movable rack bar 54, the collar 53 being so constructed that the shaft may rotate without rotating the rack bar, but a longitudinal 35 movement of the shaft causes a corresponding movement of the rack bar. The rack bar engages with a pinion 55, so mounted on the outer end of the piston 12 that the latter may move freely therethrough but cannot 40 rotate in respect thereto. The shaft carries a collar 35^a rigidly connected thereto, and within the upper end of the controlling lever 31^a is a collar 32^a, free to rotate on the shaft. A centrifugal governor, including 45 weights or balls 36^a, is connected to the two collars in such a manner that when the lever 31^a is held stationary, a variation in the speed of the engine tends to move the shaft and the rack bar longitudinally. A movement 50 of the rack bar rotates the pinion 55, the piston 12 keyed thereto, and the casing section 15 which is held from rotation in respect to the shaft by means of the flange 19. As the casing section 15 is threaded to the 55 casing section 14, a rotation of the former moves it longitudinally and varies the normal position of the piston 12 and the limits thereof. This advancement or recession of the piston 12 varies the time at which the 60 gas within the cylinder 11^a will be raised to the ignition point.

In the form of the device illustrated in Fig. 2, the cam 27 serves to move the piston 12 outward against the action of the spring, 65 in starting the engine in operation or in

case of a misfire; but the piston is normally moved outward, that is, after each explosion, by the pressure existing in the cylinder at the time of explosion, and the cam merely serves to retain the spring under compression and then releases it at the desired instant. In order to move the piston outward by the pressure of the gas in the cylinder at the starting of the engine or under a misfire, and also to eliminate all 70 connections between the piston and a moving part of the device, I provide the mechanism shown in Figs. 4 to 10, inclusive, in which a second piston is provided for aiding in forcing the piston outward during 75 the compression of the main charge, and a third piston is provided for releasing or tripping the ignition piston at the time when a compression and an ignition of the charge is desired. In the specific form illustrated for accomplishing these results, the body 10^a is designed to be threaded through an aperture in the wall of the engine cylinder and is provided with an ignition cylinder 11^b, terminating within the engine cylinder and having an exhaust port 13^b through which the gases may escape at the instant of explosion. A hollow piston 12^b is employed for compressing the ignition charge within the cylinder 11^b, the face of 80 the piston being formed by a valve 21. To the body is secured a casing 14^b, within which are contained all of the parts necessary for the withdrawal of the ignition piston, the releasing of the same, the automatic 85 governing of the time of release, and also means for cooling the working parts. The ignition piston 12^b is forced inward to create the necessary pressure for bringing about ignition, by means of a spring 18^b, the 90 strength of which is in excess of the compression pressure in the engine cylinder prior to the explosion. To compress this spring and withdraw the ignition piston for starting the engine or after a misfire, I employ a second cylinder 56, the lower end of 95 which is in open communication with the engine cylinder through a passage 57, and within the cylinder is a piston 58, having a passage therethrough controlled by a downwardly-opening spring-pressed valve 59. A piston rod 60 is secured to the piston 58 and carries means for operatively connecting it to the ignition piston 12^b, so that both combine in compressing the spring 18^b during 100 the compression of the gas in the engine cylinder. This connecting means preferably comprises a plate 61, held between guides on the piston rod 60 and movable transversely thereof. One end of the plate is 105 normally held beneath a catch 62 on a part of the ignition piston 12^b, by the action of a small spring 63. The plate is in engagement with the under side of the catch when the pistons 12^b and 58 are in their inner 110 115 120 125 130

most positions, and as the gas is compressed within the working cylinder, the pressure is exerted against both of the pistons, and the two together serve to compress the spring 18^b. For disengaging the plate 61 from the catch 62 and permitting of a free return of the ignition piston, a transverse frame 64 in the casing carries a downwardly-extending pin 65, the lower end of which is tapered and adapted for insertion within an opening 66 in the plate 61. When the pistons approach the outermost positions, the pin enters the aperture and the cam or beveled surface of said pin moves the plate 10 laterally to release the ignition piston. For holding the piston 58 in its outermost position until after a misfire, the piston rod 60 is provided with a shoulder 67, adapted for engagement with a sliding 20 plate 68 carried by the transverse frame 64. The plate is normally pressed into operative position by a small spring 69, but is moved out of operative position to permit the return of the piston 58 by a 25 cam 70, carried by an arm 71 rigid with the ignition piston. When the ignition piston reaches its innermost position, the cam 70 engages with one side of the plate 68 to move the latter out of engagement with the 30 catch 67 and the piston 58 returns to the position illustrated. For aiding the piston 58 in the return movement, the outer end of the piston rod terminates within a tube 72 carried by the outer casing section 15^b. 35 Within the tube is a coil spring 73, the tension of which is controlled by an adjusting plug 74 at the outer end of the spring. For retaining the ignition piston 12^b in its outermost position and retaining the spring 18^b 40 under compression until it is desired to ignite the charge, I preferably provide a lever 75, pivoted within the frame 64 and having a hook-shaped lower end adapted to engage with a shoulder 76 carried by a part 45 of the ignition piston. A spring 77 normally holds the lever in its operative position. For releasing the ignition piston at the proper instant, I provide a third cylinder 78, similar to the cylinder 56 and 50 having a piston 79 therein similar to the piston 58. The lower end of the cylinder is at all times in open communication with the engine cylinder and the piston is connected to a piston rod 80, extending to the outer 55 end of the casing and engaging a tube or sleeve 81, similar to the tube 72. Within said tube is a spring 82, the tension of which is controlled by a threaded plug 83. Journaled on a shaft 84 (see Figs. 6 and 8) is a 60 wheel 85, the periphery of which engages with the side of the piston rod 80, and said rod is provided with a cam 86 for moving the wheel and the upper end of the lever laterally to disengage the lower end of the 65 lever from the shoulder 76, upon the out- ward movement of the piston 79 to the required extent. To prevent the wheel from traveling backward over the cam upon the descent of the piston 79, the piston rod preferably carries a guiding flange 87, extending 70 along one side of the piston rod to the base of the cam; then diagonally across the face and along the opposite side. The wheel 85 is longitudinally movable on its shaft against the action of a spring 88, and as it 75 travels up the face of the cam it is moved axially until it slips off the edge of the rod and permits the return movements of the lever. Upon the return movement of the cam, the wheel stays against the edge of the 80 cam until it is past the same, at which time it moves laterally across the face of the piston rod, but without moving the lever 75. For delivering the explosive charge through the hollow piston 12^b, the outer end of said piston is left open and telescopes within a stationary tube 89; the outer end of which may be connected to the main supply pipe or to the carbureter. For automatically governing the engine by varying the time at 85 which the ignition takes place and at the same time for cooling the working parts within the casing, I provide a fly-wheel 90 carried by a tube 91 encircling the tube 89 and longitudinally movable thereon, the 90 spokes of said fly-wheel being set at an angle so as to constitute a fan. The tube 91 is normally held in its raised position by a spring 92 and is rotated by the vibrations of the lever 75. A portion of the tube 91 is 95 formed with ratchet teeth in its periphery, as illustrated in Fig. 6, and two rack bars 93 engage with opposite sides of the tube. The two rack bars are preferably formed of a single piece of spring metal bent to substantially U-shape and having the middle or central portion pivoted to the upper end of the lever 75 and the interior portion supported on a transverse guide 94. The teeth of the two rack bars are oppositely disposed, so that the tube and fan will be rotated continuously in the same direction as the rack bars are moved back and forth. The rotation of the fan draws air into the casing through perforations adjacent the 100 lower end thereof and ejects the air from the open top of the casing, thus serving to cool the parts. The resistance to the movement of the air causes an end thrust on the fan and tube 91 and against the action of the 105 spring 92, and as the fan is rotated at a speed dependent upon the speed of the engine, this end thrust is utilized for automatically governing the engine. The shaft 110 94 supporting the wheel 85, is free to move 115 up and down in slots in the lever 75 and is also free to move laterally in slots in two arms 95 carried by a collar 96 fitting loosely in a groove in the tube 91. As the tube is 120 raised or lowered by a variation in the end 125 130

thrust; the elevation of the shaft 84 and the wheel 85 is varied, and thus the time at which the lever 75 is rocked to release the ignition piston 12^b, is controlled.

In brief, the complete operation of the form shown in Figs. 4 to 10, inclusive, is as follows: Upon the compression of the charge within the engine, the pressure is communicated to the three pistons in the 10 casing, and the pistons 12^b and 58 combine to compress the spring 18^b until the shoulder 76 engages with the catch of the lever 75. At this time, the pin 65 withdraws the plate 61, disengaging the piston 58, but the return of this piston is prevented by the engagement of the shoulder 67 with the plate 68. The tension of the spring 82 is such that the piston 79 is moved outwardly to bring the cam 86 into engagement with the wheel 85, 20 and release the lever 75 at the time it is desired to explode the charge. The descent of the piston 12^b compresses the ignition charge until it explodes, and the great increase in pressure then returns the piston 25 until the shoulder again engages with the catch of the lever 75, where it remains until again released by the action of the piston 79. Thus in the normal running of the engine, the piston 58 remains in its outermost 30 position. In case of misfire, the piston 12^b is not forced back but instead returns to its innermost position, as shown in Fig. 4, and the cam 70 acts to release the piston rod 60 so that the piston 58 can aid in 35 the compression of the spring 18^b during the compression of the next charge.

In the specific form illustrated in Figs. 4 to 10, inclusive, two separate and distinct auxiliary cylinders are employed in addition to the ignition cylinder; one of these cylinders serving to aid in the withdrawal of the ignition piston after a misfire and the other serving to operate the releasing device and permit the return of the piston. 40 If desired, I may use other means for doing the work of the piston 79, the operation of which is dependent upon the compression of gas in the igniter rather than in the engine cylinder.

I have illustrated in Figs. 11 to 13, inclusive, a device constructed as above indicated, this device including in its construction a body 10^d, the lower end of which is constructed to form an ignition cylinder 11^c. Within the cylinder is mounted the hollow ignition piston 12^c, closed at its lower end by a valve 21 and serving to compress the gas until it explodes and the flame shoots through the exhaust port 13 to the 55 interior of the cylinder. The body carries a casing 14^c, within which is formed a cylinder 100 concentric with the ignition cylinder 11^c and communicating at its lower end with the engine cylinder through a plurality 60 of passages 101. Within the cylinder is an

annular piston 102, the periphery of which engages with the inner surface of the cylinder and the central aperture of which engages with the outer surface of the ignition piston 12^c. The piston rod is in the 70 form of an annular flange 103, having packings 104, 105, upon opposite sides thereof. The inner packing 104 is held in place by a threaded sleeve 106 threaded into the flange 103 and terminating in a horizontally-disposed flange or end plate 107 extending outward to adjacent the inner surface of the casing and held from rotation by engagement with a spline or flange 108 in the latter. The packing 105 is held in place by an annular collar 105^a pressed down by a spring 109, the outer end of which engages with the inner surface of said flange or plate 107. Mounted on the plate 107 is a bracket 110, carrying a lever 111, one end of which is adapted to engage with the under side of a shoulder on the ignition piston, whereby the outward movement of the piston 102 causes a simultaneous outward movement of the ignition piston. The opposite end of the lever is adapted to engage with a roller 112 or other suitable means at the outer end of the casing for rocking the lever and withdrawing it from engagement with the ignition piston. At the outer end of the 90 casing is a depending spring arm 113, having a catch at the lower end thereof adapted to engage with a catch 114 on the plate 107 and holding the piston 102 in its outermost position, save when released after a 95 misfire. The ignition piston carries a cam 115 adapted to engage with a portion of the arm 113 to release said arm from engagement with the catch 114 and permit the descent of the piston 102 after a misfire. For 100 holding the ignition piston in its outermost position and timing the release thereof, I provide an air chamber 116 at the outer end of the casing and adapted to receive the outer end of the ignition piston. Within 110 the chamber are two or more depending spring catches 117, adapted to enter the end of the ignition piston and engage beneath a terminal flange therein for locking the piston in its outermost position. Within the 115 ignition piston is a plunger 118, normally pressed outward by the action of a suitable spring and having a conical recess 119 in its outer end, so formed that as the plunger is forced outward by the action of its 120 spring, it engages with the spring catches 117 and forces them inward to release the ignition piston. The operation of the plunger 118 is dependent upon the pressure of the air in the air chamber, which may be controlled by providing a spring-pressed air inlet valve 120 and an 125 exhaust valve 121 having a very minute passage therethrough. As the ignition piston is forced outward, the compression of 130

the air in the air chamber 116 forces the plunger downward and permits the piston to become locked in its outermost position, as illustrated in Fig. 12. At about the same time the lever 111 is withdrawn and the catch 114 engages with the catch 113 to hold the piston 102. The spring of the plunger 118 forces the air in the chamber 116 out through the small exhaust opening 10 until the plunger engages with the spring catches and the piston 12^c is released to ignite the charge. By controlling the aperture through the exhaust valve 121, the time required for the plunger to reach the 15 spring catches and release them, may be readily controlled, and thus control the time of ignition. If desired, the inner surface of the ignition piston may be provided with a longitudinal groove 122 to permit an escape 20 of a portion of the air past the plunger when it reaches a certain limit. The explosive mixture may be supplied to the interior of the ignition piston and past the valve 21 to the ignition chamber in any 25 suitable manner. As shown, a conduit 123 delivers such mixture to an annular chamber 124 within the body 10^d, from which it may escape through a plurality of apertures to the exterior of the cylinder 100 and 30 thence through apertures 20^c in the ignition piston to the interior of the latter.

Having thus described my invention, I claim as new and desire to secure by Letters Patent:

35 1. The combination with an internal combustion engine having a cylinder provided with an opening extending through the wall of said cylinder independent of the inlet or exhaust port thereof, of an ignition device 40 extending through said opening and detachably secured to said engine cylinder by its engagement within said opening and having a port delivering to said engine cylinder, a hollow piston within said ignition device, a 45 valve at the inner end of said piston, means for delivering an auxiliary charge of explosive mixture through said hollow piston to said ignition device, and means for operating said piston for compressing said 50 charge to the point of ignition.

2. An ignition device for internal combustion engines, comprising an ignition cylinder adapted to be detachably secured to the engine cylinder and having a port communicating with said engine cylinder, a hollow piston within said ignition cylinder, a valve controlling the inner end of said piston, means for moving said piston in one direction, and a spring for moving said piston 55 ton in the opposite direction to compress said charge to the point of ignition.

3. An ignition device for internal combustion engines, comprising a body adapted to be detachably secured to the engine cylinder and having an ignition cylinder pro-

vided with a port and delivering to said engine cylinder, a piston within said ignition cylinder, a casing at the outer end of said body and encircling said piston, means for delivering an explosive mixture to said casing, means for moving said piston in one direction, and a spring within said casing and moving said piston in the opposite direction. 70

4. An ignition device for internal combustion engines, comprising a body adapted 75 to be detachably secured to the engine cylinder and having an ignition cylinder extending into said engine cylinder and having a port delivering to said engine cylinder, a piston within said ignition cylinder, a casing at the outer end of said body and encircling said piston, said casing having an inlet port outside of the engine cylinder for the admission of a fuel charge, and means outside of the engine cylinder and within said 80 casing for operating said piston to compress a charge in the ignition cylinder to the point of ignition.

5. An ignition device for internal combustion engines, comprising a body adapted 90 to be detachably secured to the engine cylinder and having an ignition cylinder extending into said engine cylinder and having a port delivering to said engine cylinder, a piston within said ignition cylinder, a casing 95 at the outer end of said body and encircling said piston, said casing having an inlet port outside of the engine cylinder for the admission of a fuel charge, and a spring within said casing and in engagement with said piston for forcing the latter inward to compress the ignition charge. 100

6. An ignition device for engines, comprising an ignition cylinder adapted to be detachably secured to the engine cylinder, a 105 casing at the outer end of said cylinder, a hollow ignition piston within said cylinder and extending through said casing and having the inner end thereof closed by an explosive charge inlet valve, a spring within 110 said casing and in engagement with said piston for moving the latter to compress the charge, and means for delivering an explosive charge to the interior of said piston.

7. An ignition device for engines, comprising an ignition cylinder having a port communicating with the engine cylinder, an ignition piston within said ignition cylinder, a coil spring for operating said piston to compress the ignition charge to the point 120 of ignition, an auxiliary cylinder in open communication with the engine cylinder, an auxiliary piston within said auxiliary cylinder, and means operatively connecting said last-mentioned piston to said ignition piston, 125 whereby upon the compression of the charge in the engine cylinder, both pistons coöperate to compress said spring.

8. An ignition device for engines, comprising an ignition cylinder having an inlet 130

- port outside of the engine cylinder and a port communicating with the engine cylinder, an ignition piston within said ignition cylinder, a coil spring for operating said 5 piston to compress the ignition charge to the point of ignition, an auxiliary cylinder in open communication with the engine cylinder, an auxiliary piston within said auxiliary cylinder, means operatively connecting 10 said last-mentioned piston to said ignition piston, whereby upon the compression of the charge in the engine cylinder, both pistons coöperate to compress said spring, means for detaching said pistons when said 15 spring is under compression, and means for releasing said ignition piston to compress the charge.
9. An ignition device for engines, comprising an ignition cylinder having a port 20 communicating with the engine cylinder, an ignition piston, a spring for operating said ignition piston, means operable upon an increase in pressure in the engine cylinder and operatively connected to said ignition piston, 25 for aiding in the compressing of said spring, means for releasing said ignition piston to cause the compression and ignition of the ignition charge, and means for automatically governing said releasing means to vary 30 the time of ignition.
10. An ignition device for engines, comprising an ignition chamber having a port communicating with the engine cylinder, an ignition piston, a spring for operating said 35 ignition piston, means operable upon an increase in pressure in the engine cylinder and operatively connected to said ignition piston for aiding in the compression of said spring, means for releasing said ignition piston 40 to cause the compression and ignition of the ignition charge, means for automatically governing the action of said releasing device, and means for manually controlling said releasing device.
- 45 11. An ignition device for internal combustion engines, comprising an ignition cylinder adapted to be detachably secured to the engine cylinder and having a port communicating with said engine cylinder, a piston 50 within said ignition cylinder and having a passage therethrough, a valve controlling said passage, means for moving said piston in one direction, and a spring for moving said piston in the opposite direction, to compress the charge in the ignition cylinder to the point of ignition. 55
12. An ignition device for engines, comprising an ignition cylinder, an ignition piston within said ignition cylinder, a spring for operating said piston to compress the ignition charge to the point of ignition, a passageway leading from the ignition cylinder, whereby upon an explosion within the latter, said piston acts to compress said spring, a catch to hold said ignition piston 60 and means for releasing said catch.
13. An ignition device for engines, comprising an ignition cylinder having a port 70 communicating with the engine cylinder, an ignition piston within said ignition cylinder, a coil spring for operating said piston to compress the ignition charge to the point of ignition, an auxiliary cylinder in open communication with the engine cylinder, an auxiliary piston within said auxiliary cylinder, means operatively connecting said last-mentioned piston to said ignition piston, whereby upon the compression of the charge in the engine cylinder, both pistons coöperate to compress said spring, means for 75 detaching said pistons when said spring is under compression, means for holding said pistons, means for releasing said ignition piston and means operated by said ignition piston for releasing said auxiliary piston. 80
14. An ignition device for engines, comprising an ignition cylinder having a port communicating with the engine cylinder, an ignition piston within said ignition cylinder, a coil spring for operating said piston to 85 compress the ignition charge to the point of ignition, means for compressing said spring upon the compression of the charge within the engine cylinder and means for compressing said spring upon the explosion of the charge within said engine cylinder. 90
